(57) **CLAIM**

The ornamental design for the digital laser image projector as shown and described.

DESCRIPTION

FIG. 1 is a perspective rear view of the digital laser image projector in a first configuration showing the Cover Lid closed;

FIG. 2 is a perspective front view thereof;

FIG. 3 is a top view thereof;

FIG. 4 is a bottom view thereof;

FIG. 5 is a rear view thereof;

FIG. 6 is a front view thereof;

FIG. 7 is a right side view thereof; and

FIG. 8 is a left side view thereof.

FIG. 9 is a perspective rear view of the digital laser image projector in a second configuration showing the cover lid open;

FIG. 10 is a perspective front view thereof;

FIG. 11 is a top view thereof;

FIG. 12 is a bottom view thereof;

FIG. 13 is a rear view thereof;

FIG. 14 is a front view thereof;

FIG. 15 is a right side view thereof; and,

FIG. 16 is a left side view thereof.

The features shown bounded by broken lines or in broken lines depict portions of the digital laser image projector that form no part of the claimed design.
